J. F. Selvidge,
Inventor

By *Chasnow Co.*
Attorney

UNITED STATES PATENT OFFICE.

JOHN F. SELVIDGE, OF OLYMPIA, WASHINGTON.

HOOK.

Application filed July 10, 1922. Serial No. 573,860.

To all whom it may concern:

Be it known that I, JOHN F. SELVIDGE, a citizen of the United States, residing at Olympia, in the county of Thurston and State of Washington, have invented a new and useful Hook, of which the following is a specification.

This invention relates to hoisting hooks, and aims to provide novel means for locking the hook to the article to which the same is applied, to insure against the hook becoming released from its hold.

Another object of the invention is to provide a locking means of this character which may be readily and easily moved into and out of operation, by the operator, novel means being provided for securing the locking means in its operative position.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawing:—

Figure 1 is a side elevational view of a hook constructed in accordance with the present invention.

Figure 2 is a plan view thereof and disclosing the locking finger in its inactive position, by dotted lines.

Referring to the drawing in detail, the reference character 5 indicates the body portion of the hook which is formed with an eye 6 affording means, whereby a cable or other flexible lifting element may be secured to the hook.

The hook is formed with a reduced portion 7 adapted to accommodate the locking member 8 which is formed with a suitable opening to receive the reduced portion of the hook 7 to permit the locking member 8 to be easily moved with respect to the hook member.

Formed on the body portion at a point adjacent to one extremity of the reduced portion 7 is a shoulder 9 which shoulder is designed to cooperate with the locking finger 10 carried by the locking member 8, to hold the locking member 8 in its active position, it being understood however that the locking finger 10 is pivotally supported

as by means of the threaded shank 11 to permit the same to be moved to a position as indicated in dotted lines by Figure 2 of the drawing. Thus it will be seen that as 60 the locking finger 10 is moved out of engagement with the shoulder 9, the locking member 8 may be moved longitudinally of the reduced portion 7 to bring the outer end of the locking member 8 to a position 65 out of contact with the free end 12 of the hook member.

This locking member is formed with an opening to accommodate the free end of the body portion 5 to hold the locking member 8 in its locked position. Carried by the locking member 8 is a stationary pin 14 acting as an abutment for the locking finger 10 to prevent the same from being moved in one direction. Associated with the pin 14 is 75 a sliding pin 15 which is positioned in a suitable opening in the body portion 8 and is formed with a head 16 acting as a support for one end of the coiled spring 17, the opposite end thereof contacting with the screw 80 18 which is positioned in the threaded opening in which the coiled spring 17 is disposed, the screw 18 being provided to regulate the tension of the spring 17 to control the action of the pin 15.

From the foregoing it will be seen that by pressing downwardly on the pin 15, the free end thereof may be moved to a position flush with the upper surface of the locking member 8, whereby the locking finger 10 may be pivoted or moved out of engagement with the shoulder 9.

Having thus described the invention, what is claimed as new is:—

1. A hook comprising a body portion formed with a reduced section, a pivoted locking member mounted on the reduced section, said locking member adapted to move to engage the free end of the hook, and means carried by the locking member and contacting with the hook adjacent to the reduced section thereof for securing the locking member in its locking position.

2. A hook comprising a body portion formed with a reduced section, a locking member mounted on the reduced section and adapted to move longitudinally thereof, one end of the locking member adapted to cooperate with the free end of the hook for closing the hook, and means for restricting movement of the locking member longitudinally of the reduced section.

3. A hook comprising a body portion formed with a reduced section, a locking member pivotally supported on the reduced section, the locking member adapted to contact with the free end of the hook to close the hook member, said locking member adapted to move longitudinally of the reduced section to permit the locking member to be moved out of engagement with the free end of the hook member, and a locking finger for restricting movement of the locking member.

4. A hook comprising a body portion formed with a reduced section, a pivoted locking member mounted on the reduced section and adapted to swing to engage the free end of the hook member, a pivoted locking finger carried by the locking member, a shoulder on the hook and adapted to be engaged by the locking finger to restrict move-

ment of the locking member, and means for restricting movement of the locking finger.

5. A hook comprising a body portion, a locking member pivotally supported on the hook and adapted to move into engagement with the free end of the hook, a pivoted locking finger supported on the locking member, a shoulder on the body portion and adapted to be engaged by the locking finger to restrict movement of the locking member, and spring controlled means for restricting movement of the locking finger.

In testimony that I claim the foregoing as my own, I have hereto affixed my signature in the presence of two witnesses.

JOHN F. SELVIDGE.

Witnesses:

FRANK TANNER,
C. A. MCFERRAN.
